UNITED STATES PATENT OFFICE

2,287,001

KNITTING MACHINE

Robert H. Lawson, Pawtucket, and Arthur N. Cloutier, Lonsdale, R. I., assignors to Hemphill Company, Central Falls, R. I., a corporation of Massachusetts

Application November 30, 1929, Serial No. 410,819
Renewed November 26, 1938

11 Claims. (Cl. 66—135)

This invention relates to knitting machines of the type disclosed in the patent to Hemphill 933,443 September 7, 1909, and more specifically to an improvement thereover disclosed in the patent to Lawson et al. 1,702,608, February 19, 1929.

The mechanism herein disclosed although primarily adapted to be used in connection with rotating needle cylinder machines is not necessarily limited thereto, but may be used in connection with knitting machines of the so-called revolving cam type and furthermore is not necessarily limited to circular knitting machines.

In the drawings:

Fig. 1 is a view in front elevation of the knitting machine, the main cam shaft and connections therefrom for timing and controlling the usual knitting operations not being shown;

Fig. 1a is a plan view partly in section showing mechanism for controlling the selection of needles;

Fig. 2 is a view in side elevation of mechanism for feeding clocking or other striping threads to certain selected needles;

Fig. 3 is a top plan view of the parts shown in Fig. 2;

Fig. 4 is a detail view of one form of the means employed for feeding the clocking or other threads to the needles;

Fig. 5 is a view similar to Fig. 4 but showing a different position of the parts;

Fig. 6 is a plan view of the guide carrier of Figs. 4 and 5;

Fig. 6a is a detail view showing the relative positions of the wrap stripe guides and the needles, the guide carrier for wrapping the thread around selected needles being the one shown in detail in Figs. 4, 5 and 6.

Fig. 7 is a view similar to Fig. 4 but of a modified form of thread feeding means;

Fig. 8 is a view partly in section of the feeding means shown in Fig. 7 but showing a different relative position of the parts;

Fig. 9 is a sectional view of certain connections;

Figs. 10, 11, 12, and 13 are detail views of the mechanism shown in Figs. 7, 8, and 9;

Fig. 13a is a view similar to Fig. 6a but showing the form of guide carrier specifically disclosed in Figs. 7-13 inclusive.

Fig. 14 is a conventional view of a stocking having clocking areas knit therein;

Fig. 15 is an enlarged view of the fabric structure;

Fig. 16 is a view of thread floats at the inner side or face of the stocking and resulting from the operation of the mechanism shown in Figs. 4, 5, and 6; and

Fig. 17 is a view similar to Fig. 16 but resulting from operation of the mechanism shown in Figs. 7-13 inclusive.

The numeral 1 designates the knitting machine generally, 2 the circular base on which is mounted in the usual manner a needle cylinder 3, sinker head 4 and latch ring 5, the latter being retained in lowered, operative position by means of a latch 6 engaging over a pin 7 carried by the mouthpiece 8 which is an extension of the latch ring. The mouthpiece 8 carries the usual yarn levers 9 adapted to feed threads 10 including body and plating threads, heel and toe threads, and such striping threads as may be interchangeably knit in from time to time.

Carried by an extension of the circular base or bobbin stand 2' is a drum 11 mounted to turn upon a vertical axis and racked from course to course or as desired by a pawl means 12 suitably controlled from the "104" gear and in engagement with ratchet teeth 12'. The drum 11 has mounted on its surface or periphery cams 13, 14 and 15. The cams 13 are adapted to engage arms of levers 16 pivoted at 17 upon a vertically disposed pin 17 mounted in lugs 18 forming part of a bracket 19 which is fastened to the yarn lever box 20 while the other arms of the levers 16 engage other levers 21 pivoted intermediate their ends at 22. Engagement of one arm of a lever 16 by a cam 13 rocks the said lever 16 upon its pivot, whereupon the other arm of the lever rocks a corresponding lever 21 upon its pivot against the tension of a retractile spring 23, one end of which is connected to one arm of the lever 21 while the other end of the said spring is connected to a vertically disposed post 24 attached to the circular base as at 25. The rocking of a lever 21 causes a pin 26 depending from the other arm thereof to engage and move a corresponding slide 27 which carries a jack raising cam 28 at its inner end adjacent the cylinder. Jacks mounted within the slots of the needle cylinder and beneath the needles have butts 28' thereon located at different elevations. At one such elevation butts are in position to be engaged by the lowermost cam 28 while the other butts are correspondingly positioned to be engaged by the other cams 28. The engagement of the jack butts by the cams 28 causes the said jacks to be raised, which jacks in turn raise their needles to an elevated position all as disclosed in Fig. 41 of the Lawson Patent 1,702,608 for the purpose of taking and knitting in the lap or wrap stripe threads or yarns.

Mechanism for carrying out the method and knitting the product with which this invention is especially concerned is specifically disclosed in Figs. 2-13 inclusive, wherein 29 and 61 designate supplemental or wrap stripe thread guide carriers or discs carrying depending, porcelain or other eyes 30, 62 and 70 by means of which supplemental threads or yarns 31 are fed to needles selectively raised as hereinbefore described.

Whereas in the Lawson Patent 1,702,608 the carrier 111 corresponding to carrier 29 is shown as mounted to rotate in time, preferably, one and one with the needle cylinder, so that the same yarn will always be fed to or wrapped around the same raised needles, the mechanism herein disclosed changes the yarn or thread fed to or wrapped around the certain selected needles so that in the clocking or other areas or stripes the threads 31 are interchangeably knit in by the selected needles whereby in a lengthwise extending stripe threads or yarns 31 of different colors may be knit in.

In the form specifically disclosed in Figs. 4, 5, and 6 the desired thread or yarn change is the result of a circumferential shifting of the disc or guide carrier 29, so that a certain guide eye 30 feeds its thread to or wraps it around certain selected needles for a desired number of courses and thereafter a second guide eye 30, preferably the eye next adjacent to the first mentioned eye, feeds its thread to or wraps it around the same group of needles theretofore having knit in the first mentioned clocking or striping thread. In this manner a clocking thread 31 of one color will be knit in by the needles knitting, say, the central clocking area A, Fig. 14, for a few courses, which clocking thread plates over the thread or threads constituting the body of the stocking or other fabric; thereafter a clocking thread of another color will be wrapped around the selected needles by the second mentioned eye 30, and plate over the said body thread or threads for a desired number of courses. Thus the first and second mentioned clocking threads 31 each replace the other at intervals.

The means specifically disclosed in Figs. 4, 5, and 6 to change the color of the clocks includes an upper disc 32 and a lower disc 33 which two discs 32 and 33 clamp between them the heads of the porcelain eyes 30 and thereby rigidly maintain them in proper position. Rising vertically from and rigidly connected to the lower disc 33 is a shaft 34 and surrounding the same and fastened thereto as by a screw 35 is a hub 36 which maintains the upper disc 32 in clamping engagement with the heads of the porcelain eyes 30. Shaft 34 is received within a hole 37 provided in a sleeve or shaft 38 which is in alignment with the hub 36 but is prevented from turning therewith. The shaft 38 provides a suitable bearing for the shaft 34 to which turning movements are imparted by means of a pin in the form of a screw 39 fast to the said shaft 34, the outer end of which pin 39 projects radially through a horizontally disposed slot 40 provided in the shaft 38 and also through a diagonally disposed or inclined slot 41 provided in a hub 42 carried by a grooved disc or yoke 43. The disc 43 carries supplemental porcelain eyes 44 through which the threads 31 pass on their way to the first mentioned eyes 30. The guide carrier 29, as hereinbefore stated, is driven to rotate one and one with the needle cylinder and by mechanism similar to or identical with that disclosed in the patent to Lawson 1,702,608, but the means for so rotating the guide carrier 29 in time with the needle cylinder is not a necessary part of the present invention and is not disclosed specifically herein. As the yoke or disc 43 is raised or lowered to and from the positions of Figs. 4 and 5 the walls of the inclined slot 41 engage the head of the screw or pin 39 and cam the said pin 39 to or from the positions of Figs. 4 and 5 thus causing the stub shaft 34 to which the pin or

5 screw 39 is connected to rotate or move through an arc determined by the length and inclination of the slot 41. The hub 42 and yoke 43 are held from turning on the sleeve or shaft 38 by means of a keyway 45 provided in shaft 38 and a pin or screw 46 passing through the yoke 43 and into the said keyway 45. As shown in Fig. 6 eight porcelain eyes 30 are circumferentially arranged around the carrier 29 and equi-distantly spaced. Accordingly the slot 41 is adapted to move the carrier disc 29 through an arc of approximately 45 degrees thereby causing the next adjacent eye 30 to assume the exact position, with respect to certain needles, as was occupied by the eye 30 which previously fed a wrap or supplemental thread to the said certain needles. However, the circumferential movement of the guide carrier 29 due to the inclined slot 41 and pin 39 may be more or less depending upon the number, arrangement and disposition of the eyes 30 in the carrier 29.

20 The means for periodically raising and lowering the yoke or disc 43 is specifically disclosed in Figs. 2 and 3, wherein a lever 47 is provided with arms 47' the ends of which carry pins 48 that project into the groove of the disc or yoke 43. The lever 47 is normally maintained in lowered position by means of a spring 49 one end of which is attached to a pin 50 carried by the said lever 30 47 and the other end of which is attached to a convenient part of the machine frame. The said lever 47 is pivoted at 51 to an upright bracket 52 carried by the circular base to which bracket is also pivoted a lever 53 having at one end thereof a pin 54 engaged within a groove of a disc 55 fast to the shaft 38 so that upon elevation of the disc 55 the guide carrier 29 is raised to a position above the needles. The lever 53 controls the upward movement of the disc 55 and guide carrier 29 as and when dictated by pattern mechanism not shown and not of itself a part of the present invention. The disc 55 is raised prior to levelling needles for transfer and heel and toe knitting. Pivoted coaxially with the lever 47 upon the pivot 51 is a lever 56 which is provided with a laterally extending lug 57, with which the underside of the lever 47 is normally held in engagement by means of spring 49. The lever 56 depends freely from its pivot 51 and at its lower extremity is normally in contact with one arm of a second and horizontally disposed lever 58 pivoted at 59, intermediate its ends, to a post upstanding from the circular base, the other arm of lever 58 having a lug 60 in engagement with the surface of the drum 11 or cams 14 thereon. When in engagement with the surface of the drum 11, as shown in Fig. 3, the lever 56 maintains a true vertical position as shown in Fig. 2, the spring 49 at such time maintaining the lever 47 in lowered position and consequently with the parts in the position shown in Figs. 2 and 4. When, due to the racking movements imparted to the drum 11 by the pawl and ratchet 12, a cam 14 engages the lug 60 of the lever 58 and rocks the latter, the other arm of the said lever swings or rocks the lever 56 to such a position as to cause the lug 57 thereon to raise or elevate the lever 47, which lever in turn raises the disc 43 from the position shown in Fig. 4 to that of Fig. 5 with the result that the clocking or other thread or yarn 31 previously fed to or wrapped around the certain selected needles for the desired number of courses is angularly displaced and to such a position with respect to the needles as to wrap around another group of

selected needles, while a second thread 31 adjacent to the first, at the same time wraps around the group of needles first mentioned.

In Figs. 7-13 inclusive is disclosed a modification of the means for changing the color of the clocking or other stripes which modified means includes a guide carrier 61 corresponding in some respects to guide carrier 29 of Figs. 4 and 5. Porcelain or other thread guiding eyes 62 are held between two plates or discs 63 and 64 clamped against the opposite sides of the heads of the eyes by means of a knurled screw 65 the shank of which threadedly engages a stub shaft or rod 66 received within a hole 67 provided in a sleeve or shaft 68. The shaft 68 turns one and one with the needle cylinder, and carries around with it the stub shaft 66 and discs 63 and 64. The stub shaft is made fast to the shaft 68 as by means of a set screw 69, and the porcelain eyes 62 thus, from course to course, maintain the same positions, with respect to their needles in the needle cylinder so as to wrap clocking or other threads around the same groups of selected needles. In other words, a porcelain eye is always in position to feed thread to or wrap thread around the same group of needles, whereas in Figs. 4 and 5 the corresponding eyes 30 are shifted circumferentially through an angle of approximately 45 degrees to change the thread or yarn wrapped around selected groups of needles.

In addition to the relatively fixed porcelain eye 62 there are provided additional thereto other and interchangeable, steel eyes 70 two sets of two each being disclosed in the drawings although any desired number of pairs obviously may be utilized if desired. The steel eyes 70 depend from and are carried by levers or guides 71 slotted as at 72 at their inner ends and within which slots, pins or screws 73 are received. The screws 73 control the in and out interchangeable movements of each pair of steel eyes and threadedly engage and pass through corresponding holes provided in a plate or disc 74 which is recessed at 75 to receive and house an idle eye 70 of each pair while the other such eye is in the active feeding position all as shown in Fig. 10. The plate 64 is shown as provided with V-shaped slots 76 within which slots thickened portions 77 of the levers 71 are received and guided in their movements to and from feeding positions. The thickened portions 77 provide shoulders 78 which abut against the ends of the slots 76 when the levers 71 are in retracted position, and the inner ends of the said levers are reduced beyond the shoulders as at 79 where the said levers slide upon the upper surface of the plate 64. The plate or disc 74 is carried by a hub 80 journaled within a bearing 81 provided by the relatively fixed sleeve or shaft 68. The hub 80 terminates a short distance above the disc 74 and there engages shoulders 82 provided by the sleeve or shaft 68. Projecting radially outward from the hub 80 is a pin or screw 83 extending through a horizontally disposed slot 84 in the shaft 68 and through a diagonally disposed or inclined slot 85 provided in a hub or sleeve 86 which surrounds the shaft 68 and is fixed thereto against turning independently thereof as by means of a set screw 87 engaging a keyway 88 in the shaft 68. The screw is held in place by an additional, locking screw 89.

In the form of the invention disclosed in Figs. 7-13 inclusive, as well as in the first described form, pins 48 carried by the arms 47 of the lever 47 engage the groove of the yoke or disc 90

as determined by the cams 14 upon the drum 11 and connections therefrom, and thereby raise and lower the said disc 90 to interchange the clocking threads 31 wrapped around selected needles by means of the eyes 70. Fig. 7 shows the yoke or disc relatively raised and at such time one eye 70 of each set is in feeding position while the other eye is retracted and housed within a recess 75 provided in the plate 74. As the disc 90 and hub 86 move down from the position of Fig. 7 to that of Fig. 8 the diagonal slot 85 engages the pin 83 and cams the same to the right from the position shown in Fig. 7. The pin 83 carries with it the sleeve 80 and the disc or plate 74, which plate by means of the pins 13 engaging in the slots 72 causes one lever 71 of each pair to move from a projected position to a retracted position and simultaneously therewith moves the retracted lever 71 to a projected position. The steel eye 70 carried by the lever second mentioned is thus moved to a position to feed to or wrap its thread around the certain selected needles theretofore receiving thread through the companion eye 70.

The clocking mechanisms disclosed in Figs. 4-6 and Figs. 7-13 respectively, may each be replaced by the other by loosening a set screw 46 or 87, removing the clocking mechanism and substituting the other therefor. Furthermore the two clocking mechanisms may be used in conjunction the one with the other.

Figs. 6a and 13a illustrate how the wrap threads are carried from positions within the needle circle to positions to the outside thereof and finally back to positions within the needle circle. The needles N which are mounted within tricks or grooves in the needle cylinder 3 are arranged in a circle having a greater diameter than either guide carrier and as a consequence thereof, and the fact that the needle cylinder and guide carriers are rotated in timed relation with one another, the needles have a greater peripheral speed than the threads which pass through the eyelets in the guide carriers, the result being that the needles gain with respect to the wrap threads.

In Fig. 14 a stocking is shown having knit therein by the methods herein described a clocking area or stripe A flanked on each side by stripes B and C which stripes extend lengthwise of the stocking.

In Fig. 15 a few wales and courses are shown with the body thread 91 and the plating thread 92 knit in throughout and a third, wrap stripe thread 31 knit in at certain wales as at 93 and floated therebetween at 94. The floats 94 are the result of the failure of jacks to raise their needles to a level to knit in the wrapping thread 31, which thread consequently floats back of the threads 91 and 92 taken and knit in by all of the needles at the mouthpiece. The floats 94 constitute knitting floats or floats resulting from needle selection. In addition to the knitting floats 94, wrapping floats 95 extend from the last wale where a thread 31 is knit in in one course to the first wale where the card thread 31 is knit in in a succeeding course. Each thread 31 is adapted to be fed to and wrapped around ten to fourteen adjacent needles, the number of such needles actually knitting in a wrapping thread 31 depending upon the number of needles selected by the jacks and cams 28 as hereinbefore described. As disclosed in Fig. 15 a thread 31 spans seven wales, the first, third, fifth, and seventh wales having knit therein the said thread 31 for four courses preceded by a few

courses with the said thread 31 knit in at the second and sixth wales only.

The wrapping floats 85, Fig. 16, are shown at 96, 97, and 98. The threads 31 are knit in on the face of the fabric as stripe D, E, and F. For the first few courses indicated, Fig. 16, a separate thread 31 is fed to and wrapped around three adjacent series or groups of needles by means of the eyes 30, Figs. 4, 5, and 6, which needles are selected as hereinbefore described. During the knitting of the said first few courses the yoke 43 is in the position shown in Fig. 4. To change the colors of the stripes D, E, and F yoke 43 is shifted from the position of Fig. 4 to that of Fig. 5 thereby moving the eyes 30 circumferentially or laterally through an arc of approximately 45 degrees so that the threads 31 that theretofore were knit in as stripes D, E, and F float laterally as indicated by the numerals 99, 100, and 101 respectively. The lateral displacement of the threads 31 permits a change in the color of all the stripes D, E, and F, so that a continuation of the stripe E has knit therein the thread theretofore knit in as stripe D; while the continuation of the stripe D has knit therein the thread 31 theretofore knit in as stripe F; while the said stripe F has knit therein a thread 31 which either floated as indicated at 102 from a stripe adjacent to the stripe F (not shown) or was theretofore idle because it was not knitted by any of the needles; while the thread theretofore knit in as stripe E floats as at 100 to an idle position or to be knit in as a stripe (not shown) and adjacent to the stripe E. After knitting in the desired number of courses with the threads 31 in the second named position, they may be either returned to the first position or again shifted laterally in the same direction. If shifted back to their original positions, floats 103, 104, 105, and 106 return all four threads 31 to their original stripes. The wrapping threads 31, in all cases, float from the last wale where knit in, in one course, to the first wale where knit in, in a following course.

Operation of the clocking mechanism, Figs. 7-13 inclusive, changes the color of a given stripe such as G, Fig. 17, and avoids the objectionable floats 99-106, Fig. 16 which floats 99-106 are replaced by wrapping floats 107, 108, connected by floats 109, 110, that cross the courses and floats 107, and 108. The floats 109 and 110 extend lengthwise of the stocking or other fabric and from the last wale where knit in in one course of knitting to the first wale where knit in in a succeeding or following course. The float 109 extends in a substantially straight line from wale to wale whereas the float 110 is deflected from a straight line by the float 109 so that one part of the float 110 extends from the last wale where knit in to the float 109 and the other part or extension of the float 110 passes from the float 109 to the other side or edge of the stripe G where it is again knit in. Lengthwise extending stripes H, I are, preferably though not necessarily, knit in adjacent to the clocking area G by threads 31 which are fed to and wrapped around selected needles by the porcelain eyes 62.

The stripes D, E, F, G, H, and I may span the same number of wales from course to course as indicated in Fig. 16 or they may span an increasing or decreasing number of wales as indicated in Fig. 17.

While the body and plating threads 91, 92 are shown in Fig. 15 as knit in throughout, either one or both may be floated where the wrap stripe

thread or threads 31 are knit in or at any other desired place in the fabric for ornamental or other purposes.

The wrapping floats and floats which extend across the wales may be severed if desired.

While this invention is herein disclosed as applied to a machine of the circular, independent needle type, the invention in all respects is not limited thereto, but is also adapted to other types of knitting machines than those having independent needles arranged in a circle and furthermore while it is herein disclosed as applied to hosiery machines it is equally adapted to be used in connection with so-called body machines if desired.

We claim:

1. In a circular knitting machine of the rotary, independent needle type, means for feeding a thread or threads to the needles throughout substantially all the wales and courses, means for feeding an additional thread or threads to certain needles, said means including a rotary guide carrier having mounted therein a plurality of interchangeable thread guides, the said interchangeable thread guides each being adapted to occupy the same active, feeding position, each interchangeable thread guide thereby being adapted to feed its thread to the same group of needles, means for causing the guide carrier to rotate in time with the needle cylinder and so controlling the threads that each such thread will be interchangeably wrapped around one or more needles as desired.

2. A knitting machine having needles independently mounted therein, means for feeding a thread or threads to all of the needles, other means for feeding additional threads to certain of the needles only, said means including a rotary guide carrier, rotatable once for each course of knitting and means for circumferentially moving the guide carrier independently of the mentioned rotary movement during each course of knitting, the last mentioned means including a member movable with respect to the guide carrier, connections between the said member and guide carrier, whereby the said movements of the member are translated to circumferential movements of the guide carrier, the last named member including a yoke vertically movable and provided with a hub having therein a slot inclined to the horizontal, a pin carried by the guide carrier and in engagement with the said inclined slot, whereby reciprocating movements of the yoke cause circumferential movements of the guide carrier.

3. A knitting machine of the circular, independent needle type, means for feeding a thread or threads to all of the needles, in combination with supplemental means adapted to feed a thread or threads to certain of the needles only, the second mentioned means being adapted to be so controlled as to feed one, at least, of the said supplemental threads to one, at least, of the said certain needles for a desired number of courses and thereafter to feed another supplemental thread to the same needle or needles, means for controlling and timing the interchangeable feeding of the supplemental threads to the said group of certain needles, said means including pattern mechanism having pattern indications thereon and connections between the said pattern indications and supplemental thread feeding means to control the desired changes in the feeding of the supplemental threads, the connections between the pattern indications and

supplemental feeding means including a vertically movable member adjacent to the supplemental feeding means and immediately controlling the desired changes in the feeding of the supplemental threads, a lever adapted to raise the vertically movable member, a second lever in engagement with the first, a third lever, one arm of which is in engagement with the second lever and the other arm of which is in engagement with the pattern indications whereby the latter time and control the vertical movements of the said vertically movable member.

4. In a knitting machine of the rotary, independent needle type, means for feeding a thread to all of the needles, means adapted to feed additional threads to certain needles only and by needle wrapping movements of the said additional threads, the second mentioned means including, at least, two thread guides adapted interchangeably to feed said additional threads to and wrap them around the said certain needles, the said guides being adapted to assume a non-feeding position or a feeding position with relation to the needles, means for controlling the movements of the said guides to and from thread feeding relation with respect to the needles, the said means including a slotted member, the slots of which cause the interchangeable guides to slide to and from thread feeding relation with respect to the certain needles.

5. A circular knitting machine provided with a needle cylinder and means for rotating the same, means for feeding at least one thread to substantially all of the needles, in combination with thread guiding means to feed supplemental threads to and wrap them around some of the needles, said thread guiding means consisting of a member eccentrically mounted with respect to the needle cylinder and being driven to rotate one and one with the said needle cylinder, the supplemental threads by such circular movements of the guiding means being adapted to wrap around some of the needles, at least two thread guides being carried by said guiding means and being movable in such a manner that one such guide is companion to a certain group of needles during the knitting of one course while the other guide is companion to the same group of needles during the knitting of another course.

6. A knitting machine of the character described having a rotary needle cylinder, needles mounted therein for independent thread taking movements, means for feeding a thread or threads to the needles through substantially all the wales and courses, other means for feeding an additional thread or threads to certain selected needles and by wrapping the said thread or threads around the said certain needles, the said additional feeding means including a guide carrier movable in time with the needle cylinder, means adapted to cause the guide carrier to gain with respect to the needles whereby a thread fed to certain needles for a certain course or courses will, during the immediately following course, feed to other needles in advance of the needles first mentioned.

7. A knitting machine having needles independently mounted therein, means for feeding a thread or threads to all of the needles, other means for feeding each of additional threads to one or more of the needles, said means including a rotary guide carrier, rotatable once for each course of knitting and means for circumferentially moving the guide carrier independently of the

mentioned rotary movement during each course of knitting to effect the wrapping of a needle with one of said threads during the knitting of one course and with another of said threads during the knitting of the next course, the last mentioned means including a member movable with respect to the guide carrier, connections between the said member and guide carrier, whereby the said movements of the member are translated to circumferential movements of the guide carrier.

8. A knitting machine having in combination knitting instrumentalities, means for feeding yarn to said instrumentalities throughout a plurality of successive courses and wrap yarn feeding means eccentrically mounted and rotatable with said knitting instrumentalities equipped to feed a plurality of wrap threads to selected ones of said instrumentalities, said wrap thread feeding means having means for interchanging feeding differentiated wrap threads to the same needle or groups of needles and means operable in successive courses to feed first one of said wrap threads to a pair and then the other so that in one course one wrap thread may be knitted on any needle or needles of a group and in the next following course a different wrap thread may be knitted on any needle or needles of the same group.

9. A rotary, independent needle knitting machine having in combination knitting instrumentalities, yarn feeding means for feeding a yarn throughout a plurality of successive courses, wrap thread feeding means including an eccentrically mounted means for feeding a plurality of wrap threads rotatable in timed relation with said knitting instrumentalities, means for bodily raising and lowering said wrap thread feeding means and other means operable in accordance with a predetermined pattern for varying the relative circumferential position of said wrap thread feeding means with respect to said knitting instrumentalities.

10. In a rotary, independent needle knitting machine the combination of knitting instrumentalities and a wrap thread feeding means rotatable with said instrumentalities but eccentrically mounted with respect thereto, means for shogging said wrap thread feeding means relatively to said instrumentalities including a spirally disposed cam slot, a pin engageable in said cam slot, a collar movable lengthwise of said cam slot and within which said pin is fixed, means for preventing relative rotation of said collar and for moving the same along with said slot thereby to impart shogging movements to the wrap thread feeding means.

11. A knitting machine having needles independently mounted therein, means for feeding a thread or threads to all of the needles, other means for feeding each of additional threads to one or more of the needles, said means including a rotary guide carrier, rotatable once for each course of knitting and means for circumferentially moving the guide carrier independently of the mentioned rotary movement during each course of knitting associated with and, the last mentioned means including a member movable with respect to the guide carrier, connections between the said member and guide carrier, whereby the said movements of the member are translated to circumferential movements of the guide carrier.
